UNITED STATES PATENT OFFICE.

JOSEPH C. POLE, OF NEW YORK, N. Y., ASSIGNOR TO COOPER HEWITT ELECTRIC COMPANY, OF HOBOKEN, NEW JERSEY, A CORPORATION OF NEW JERSEY.

MERCURY-VAPOR APPARATUS.

1,110,645.

Specification of Letters Patent. Patented Sept. 15, 1914.

Application filed September 5, 1912. Serial No. 718,652.

To all whom it may concern:

Be it known that I, JOSEPH C. POLE, a subject of the Emperor of Austria-Hungary, and resident of New York, county of New York, State of New York, have invented certain new and useful Improvements in Mercury - Vapor Apparatus, of which the following is a specification.

It is well known that in a mercury vapor lamp wherein the cathode and the anode are of mercury, the difference in heat produced by the unequal drop of potential on the two electrodes generally causes a distilling of mercury from one electrode to the other so that, in order to keep a lamp of that type continuously running without one electrode being emptied out, means have to be provided for continuously or intermittently replenishing the mercury of that particular electrode which has the tendency to empty out. The tubes of lamps of this class are frequently bent into the general shape of an inverted U, the mercury electrodes being located at the bottom of the legs of the yoke and the upper part of the yoke constituting the light giving portion when the lamp is in operation. Such lamps, especially those operating at low current (about one ampere) sometimes incline, in the operating lamp, to periodical fluctuations of the mercury in the two legs of the tube. These fluctuations may cause considerable variations of the current,—so great at times, as to cause the lamp to be extinguished. Another difficulty with lamps of this type is due to the danger of fracture during transportation which danger is especially great in connection with certain types of so-called quartz lamps, wherein the lamps operate at atmospheric pressure. A considerable amount of attention has been given to the starting of lamps of this class where the current is first passed through a continuous body of mercury in a tube and means have to be provided for causing a separation of the mercury and the formation of an initial small arc which afterward extends or propagates itself in the manner now well recognized. I have devised means whereby the various desirable operations above referred to may be accomplished in a simple manner and whereby the difficulties mentioned may be overcome, also by simple means.

The details of my invention will be under-

stood by reference to the accompanying drawings in which—

Figures 1 and 2 are respectively side and front elevations of a lamp to which my invention is applied, portions of the lamp being broken away to show details; Fig. 3 is a front elevation of the same lamp illustrating more particularly electric circuits which may be used in connection therewith; Fig. 4 is a side elevation of a modified form of lamp apparatus, showing also in section a portion of the lamp to which my means for protecting the lamp during transportation are applied; Fig. 5 is a front elevation of the same lamp, sectioned at the top to show my improved means for causing the initial arc for starting the lamp.

In Figs. 1, 2 and 3, 1 is the luminous part of the lamp, the same being bent in the form of an oval with two upright legs, 2 and 3, one at each side of the bent portion of the tube. At the lower ends of the legs are curved tubes 4 and 5 extending in opposite directions and terminating, one in an upright enlargement 6 and the other in a similar enlargement, 7. These enlargements connect with each other by means of a narrow tube, 8, provided at 9 and 10 with still narrower contracted portions, as clearly shown in Figs. 1 and 3.

Depending from the center, or approximately the center, of the curve of the tube, 1, is a "teat," 11, filled with mercury, and above the teat, approximately, but preferably not quite, at the summit of the luminous tube, is a contraction, 12. The said "teat" is supplied with an electric heating spiral, 13, the connections of which appear in Fig. 3, where 14 and 15 are the leads of the source of direct current supply, and 16 and 17 constitute with the terminals 18 and 19 a double pole switch. Beyond the switch a circuit passes by way of an inductance coil 20 and an auxiliary conductor, 21, to one end of the heating spiral, 13, from the other end of which it travels by way of the conductor 22 into connection with a conductor, 23, constituting one of the main leading-in wires of the lamp. The other main leading-in wire, 24, is connected by a lead, 25, through a series resistance, 26, to the other pole of the supply. An auxiliary leading-in wire, 27, is connected by a branch, 28, to the lead, 21. Returning to the physical construction of

the lamp of Figs. 1, 2 and 3, it will be noted that the bent tubes 4 and 5, at the bottom of the structure, are provided at 29 and 30 with contractions, as shown. These contractions have a very small inside diameter, thus constricting the opening between the legs 2 and 3 of the tube and the enlargements, 6 and 7. Attention may further be called to the fact that the main leading-in wires, 23 and 24, are surrounded, where they pass down the enlargements 6 and 7 with small insulating tubes, 31 and 32. It may also be noted that the normal mercury level in a cold tube, as shown at 33, is below the point reached by 15 the end of the auxiliary leading-in wire, 27. That is to say, when the lamp is not in operation the auxiliary wire, 27, does not touch the surface of the mercury.

The operation of the lamp is the following: A certain direct current voltage, say 220 volts, being applied to the supply conductors, 14 and 15, and the double pole switch, 16, 17, 18 and 19, being closed, an electric current will first pass through the 25 coil 20, the spiral 13, the leading-in wire 23, and the mercury in the tube 1 the mercury in which then fills the whole luminous tube, to the other leading-in wire, 24, whence it passes through the resistance, 26, back to the 30 supply. The mercury in the teat, 11, being heated by the spiral, will vaporize, and the vapor bubbles, rising, will separate the mercury in the contraction, 12, and the contact of the mercury in the luminous tube being 35 interrupted, a small arc will be formed. The heat of the initial arc will increase the vapor pressure and ultimately drive the mercury from the luminous tube into the enlargements 6 and 7, until a certain equilibrium 40 between the inside mercury vapor pressure and the outside atmosphere is reached and the mercury settles, for example, at levels 35—36 and 37—38.

The height of the mercury levels depends 45 wholly, in a given case, upon the voltage applied to the lamp and upon the cooling surfaces of the lamp. When equilibrium in an operating lamp is reached, the mercury in the enlargements, 6, makes contact with the 50 auxiliary leading-in wire, 27, thus short circuiting the heating coil, 13, and stopping its operation during the time the lamp is under current.

The cooling is increased and varied by 55 heat radiating ribs, 39, of sheet metal mounted on the enlargements, 6 and 7, as shown, for example, at the left in Fig. 4.

The function of the tube, 8, now becomes 60 clear. When, for example, in my lamp, the positive pole of the supply is connected to the mercury in the enlargement, 6, the mercury level in this enlargement will generally drop and the enlargement, 7, will get filled up. This, however, will proceed only until 65 the mercury level, 38, (Fig. 3) in the en-

largement, 7, reaches the connecting tube, 8, when the mercury will enter into this tube and flow through it back to the enlargement, 6. To prevent the mercury from flowing too rapidly from one enlargement to the other, 70 I provide one or more narrow contractions as 9—10, in the connecting tube; and to prevent short circuiting between the leading-in wires, 22 24, by the mercury flowing through the connecting tubes, I protect said leading- 75 in wires by the small insulating tubes, 31 32, already described.

The enlargements 6 and 7 are of equal volume, and either one is so large that, when the mercury fills one enlargement up to the 80 connecting tube, 8, the other enlargement is not completely emptied out and still maintains safe electrical contact between the leading-in wire and the mercury. It is to be understood that the emptying out of one enlargement and the filling up of the other occurs very slowly, and the mercury does not generally flow continuously through the tube 8, but goes over in small drops and at certain intervals of time. It will also readily be seen that such a lamp is not only self 85 regulating but is also independent of the maintenance of a fixed polarity, since it is perfectly symmetrical.

The described contractions 29 and 30 in 90 the tubes 4 and 5 are provided in order to lessen the fluctuations of the mercury to a degree where they are no longer troublesome. These contractions have preferably so small an inside diameter that they allow 95 the mercury to pass but very slowly into or out of the luminous tube. In the absence of some provision of this sort, the periodical fluctuations of the mercury in the two legs of the luminous tube cause variations 100 of current which, in some instances, might result in the extinguishment of the lamp.

I have found it sometimes convenient and advantageous to replace the starting teat, 11, by a small upright tube, 40, formed on 110 the top of the luminous tube 1, as shown in Figs. 4 and 5. The heating spiral appears at 41 and may be connected in the circuit in a way similar to that of the spiral 13 described above. A small air bubble, 42, is left in the trap or, as a rule, forms of 115 itself after the lamp has been in use for some time. The mercury thus reaches only as far as the level, 43, filling, of course, the whole luminous tube, as before. When the 120 current is applied to the lamp, the heater 41 will cause the air bubble 42 to expand, drive the mercury out of the trap, and finally interrupt the contact with the mercury in the contraction, 44, of the luminous tube. This contraction like that heretofore 125 described, is preferably placed a little off the middle of the tube. The advantage of this method of starting is that it provides a small trap for gases which, in small 130

quantities, are almost always liberated from the walls of the lamp after the same has been for some time in use, and at the same time gives to the liberated gases a positive 5 function. The gases can always get out of the way and into the trap, instead of being liable to impede the starting of the lamp.

For reducing the liability of fracture or derangement of atmospheric mercury 10 lamps during transportation, I provide at the points of juncture between the tube 4 and the enlargement 6 on the one hand and the tube 5 and the enlargement 7 on the other hand, valve seats 45 and 46 adapted to 15 receive valves 47 and 48 respectively. The valves and valve seats are conical in shape and the valves are ground into the seats so as to form regular ground joints. The valve stems 49 and 50 are pushed tightly 20 downward by means of springs, one of which is shown at 51, as being held under a small cap, 52, covering the upper end of a tubular extension, 53, of the enlargement, 7. The valves and valve stems are prefer- 25 ably of iron and they serve only during transportation and may be removed after the lamp is installed,—simply by taking off the caps 52 and pulling out the rod or stems and their valves.

30 I claim as my invention:

1. In a mercury vapor lamp comprising a luminous portion, enlargements at opposite ends thereof, and mercury in said luminous portion and said enlargements, in 35 combination with a cross tube connecting the enlargements, the said cross tube being provided with constrictions.

2. In a mercury vapor lamp comprising a luminous tube, a leg on either side thereof, 40 an enlargement on each leg, and mercury in said luminous tube and partly filling the enlargements, the enlargements being joined to the main luminous tube by connecting tubes terminating at the top in

conical seats for valves, all in combination 45 with rods of iron or other suitable metal adapted to serve as valves for said seats.

3. In a mercury vapor lamp comprising a luminous tube, a leg on either side thereof, an enlargement on each leg, and mercury 50 in said luminous tube and partly filling the enlargements, the enlargements being joined to the main luminous tube by connecting tubes terminating at the top in conical seats for valves, all in combination with rods of 55 iron or other suitable metal adapted to serve as valves for said seats, and capable of forming ground joints therewith.

4. In a mercury vapor lamp comprising a luminous tube, a leg on either side thereof, 60 an enlargement on each leg, and mercury in said luminous tube and partly filling the enlargements, the enlargements being joined to the main luminous tube by connecting tubes terminating at the top in conical seats 65 for valves, all in combination with rods of iron or other suitable metal adapted to serve as valves for said seats, and means for holding the rods to their seats.

5. In a mercury vapor lamp comprising a 70 luminous tube, a leg on either side thereof, an enlargement on each leg, and mercury in said luminous tube and partly filling the enlargements, the enlargements being joined to the main luminous tube by connecting 75 tubes terminating at the top in conical seats for valves, all in combination with rods of iron or other suitable metal adapted to serve as valves for said seats, and detachable means for holding the rods to their seats. 80

Signed at New York, in the county of New York, and State of New York, this 28th day of August, A. D. 1912.
